MOTION PICTURE CAMERA OR THE LIKE

Peter Schmuck, 228 Ringstrasse, Mauren, Liechtenstein

Filed Feb. 16, 1961, Ser. No. 63,949

Claims priority, application Switzerland Sept. 27, 1960

Term of patent 14 years

(Cl. D61—1)

FIG. 1

FIG. 2

FIG. 3

FIG. 4

FIG. 5

FIG. 6

FIG. 1 is a front perspective view of a motion picture camera or the like, showing my new design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof.

The essential features of my design reside in the portions shown in full lines.

I claim:

The ornamental design for a motion picture camera or the like, as shown and described.
